[57] CLAIM

The ornamental design for a jewelry box, as shown and described.

DESCRIPTION

FIG. 1 is a top plan view of a jewelry box showing my new design, the ornamentation drawn being embossed on the under surface of the cover;

FIG. 2 is a front elevational view thereof;

FIG. 3 is a side elevational view thereof;

FIG. 4 is a rear elevational view thereof;

FIG. 5 is a bottom plan view thereof;

FIG. 6 is a top plan view with the cover raised, the ornamentation on the under surface of the cover being omitted for convenience of illustration; and

FIG. 7 is a side elevational view thereof with the cover raised.

FIG. 1

FIG. 5

FIG. 3
